UNITED STATES PATENT OFFICE.

GEORGE S. BRUSH, OF ZANESVILLE, OHIO.

DESIGN FOR A PITCHER.

Application filed September 19, 1927. Serial No. 23,469. Term of patent 3½ years.

To all whom it may concern:

Be it known that I, GEORGE S. BRUSH, a citizen of the United States, residing at Zanesville, in the county of Muskingum and State of Ohio have invented a new, original, and ornamental Design for a Pitcher, of which the following is a specification, reference being had to the accompanying drawings, forming part thereof, and in which—

Fig. 1 is a rear elevation; Fig. 2 a side view; and Fig. 3 a front elevation of the pitcher, showing the new design.

I claim:

The ornamental design for a pitcher, as shown.

GEORGE S. BRUSH.
